COMBUSTION ENGINE CYLINDER HEAD
CASING

Gustav Pielstick, Saint-Germain-en-Laye, France

Application October 5, 1949, Serial No. 119,609
In France October 12, 1948

5 Claims. (Cl. 123—90)

1

2

This invention relates to combustion engines, and more particularly to an improved casing structure for the cylinder head of a combustion engine.

In most current types of casing structures for the cylinder heads of internal combustion engines and the like, the difficulty is encountered that access may not easily be had either to the valve-operating rocker leverage or to the securing means, such as nuts or screw-studs, of the detachable cylinder head. Furthermore, known cylinder head casings of the kind described do not generally have provision for supporting the pivots or rocker shafts, of the valve-actuating rockers outside the periphery of the cylinder head; it is desirable so to support said pivots outside the cylinder head periphery.

It is an object of this invention to provide an improved casing construction for a cylinder head of a combustion engine, especially high-power engines, which ensures increased accessibility both to the cylinder head securing means and to the valve-operating rocker leverage enclosed in said casing.

Another object is to provide such a cylinder head casing construction in which the pivots for the rocking valve-operating levers may be supported from the casing itself outside the periphery of the cylinder head, so as not substantially to transmit the stresses developed by said rockers in the operation of the valves to the area of the cylinder head, but substantially outside said area.

With the above and further objects in view, I essentially provide a casing for a cylinder head which comprises generally cylindrical walls upstanding from the cylinder head and forming a coaxial extension thereof, of such a diameter as to leave the cylinder head securing means, such as screw studs or nuts, substantially outside the periphery of said casing. The casing may be a casting or a press-formed sheet metal part. It may be formed with lateral extensions and bosses to house and support the valve-operating rockers, tappets, etc. . . . I preferably provide a light-weight top cover removably sealing the casing and providing ready access to the parts contained therein.

An exemplary embodiment of my invention is illustrated by way of example and not of limitation in the accompanying drawings, in which:

Fig. 1 is a plan view of a cylinder head provided with the improved casing means, the cover of which has been removed to show the underlying valve-operating mechanism.

Fig. 2 is a vertical section on line II—II of Fig. 1.

Fig. 3 shows part of Fig. 2 in greater detail, and

Fig. 4 is a sectional view on line IV—IV of Fig. 3.

As shown by way of illustration, my improved casing structure is applied to a cylinder head 1 having the usual securing studs or the like 2 for attaching it to the engine cylinder block, intake valves 3, 4 and exhaust valves 5, 6. The operating levers or rockers for intake valves 3, 4 are shown at 7, 8 and those for the exhaust valves 5, 6 are shown at 9, 10 in the form of a two-pronged lever. The intake actuating rockers 7, 8 are pivoted on a rocker shaft 11 while the two-pronged exhaust-actuating rockers 9, 10 are pivoted on the shaft 12. The valve-lifter tappets are shown at 13.

20 The casing 14 which may be a casting or a press-formed part is secured over the cylinder head 1 by means of lugs 15 and screws 16. As shown in Fig. 1, the periphery of the casing 14 is arranged radially inwardly with respect to the 10 circumferentially-spaced cylinder head-securing studs 2, which thus remain accessible after the casing 14 is mounted in position. The cylinder head is formed with a circumferential groove 17 (see Fig. 2) containing a plastic gasket 18 or the like for sealing engagement of the casing 14 with the cylinder head 1.

As previously stated, the casing 14 is formed with bosses such as 19, 20 in its sides for providing bearings for the rocker shafts 11, 12 respectively of the intake and exhaust-operating rockers 7, 8 and 9, 10. The outer arms of these rockers are housed and operate in a lateral extension 21 of the casing. The tappets such as 13 project upwardly into said extension 21 as shown in Fig. 2.

The casing 14 is sealed by means of a top cover 22, removably secured by means of a screw-stud provided with a knurled head 23 or similar means. As shown more particularly in Figs. 3 and 4, the 35 screw 23 rigidly connects the cover 22 with a yoke-like bridging member 24 having its respective arms secured to the top of a pair of elements 25, 26 defining bearings for the rocker shaft 12 of the exhaust-valve operating lever 9, 10.

40 It will of course be understood that various modifications may be made in the structural details of the invention as hereinabove described and illustrated in connection with one specific embodiment thereof, without exceeding the scope 50 of the invention.

What I claim is:

1. In a combustion engine having a cylinder-block and a cylinder-head and means securing said cylinder head to said cylinder-block, a cylinder-head casing comprising generally cylindrical walls adapted to be secured in upstanding relation from said cylinder head concentrically therewith, said cylindrical walls being of such diameter as to leave said cylinder-head securing means radially outside the periphery of said casing walls, and means securing said cylindrical casing to said cylinder head.

2. Cylinder head casing as in claim 1 which comprises a removable top cover to seal the same.

3. In a combustion engine having a cylinder block and cylinder head and means securing said cylinder head to said cylinder block, a cylinder head casing adapted to be secured in upstanding relation from said cylinder head concentrically therewith, the walls of said casing being of such a diameter as to leave said cylinder head securing means radially outside the periphery of said casing walls, means securing said casing to said cylinder head, usual valve means and rocking control levers in said cylinder head and bosses in said casing for the pivotal mounting of said levers, said bosses being adapted to absorb the stresses resulting from the operation of said valves, said bosses being located outside the area of the cylinder head in which said valve-means operate.

4. Cylinder-head casing as in claim 3 which comprises a removable top cover to seal the same, bearing bushing means surrounding one of the pivotal means for said valve-operating levers,

5 an upward extension for said bushing means with a screw threaded hole in the top thereof, and a headed screw means extending down through said cover into engagement with said screw-threaded hole to removably secure said top cover.

10 5. In a combustion engine, a cylinder-block, a cylinder head with a peripheral securing flange and securing studs spaced around said flange, said cylinder head having an active area in which 15 valve means for said cylinder are located, pivotal rocker means for operating said valve means, and a cylinder head casing, said casing comprising generally cylindrical walls and means to secure said casing walls in upstanding relation from 20 said active cylinder head area concentrically therewith in radially inward relation to said securing studs, and means in said cylindrical walls defining bearings to support the pivots for said rocker means, said bearings overlying a region substantially outside said active area whereby the operating stresses from said rocker means are not substantially transmitted to said active area, and a lateral extension in said casing to house the outer arms of said rockers.
